UNITED STATES PATENT OFFICE.

ARTHUR R. SELDEN, OF ROCHESTER, NEW YORK.

DESIGN FOR A PLATE FOR IRONING-MACHINES.

SPECIFICATION forming part of Design No. 27,396, dated July 20, 1897.

Application filed May 24, 1897. Serial No. 637,964. Term of patent 7 years.

To all whom it may concern:

Be it known that I, ARTHUR R. SELDEN, a citizen of the United States, and a resident of the city of Rochester, in the county of Monroe and State of New York, have invented and produced a certain new and original Design for Ironing-Plates of Ironing-Machines, of which the following is a specification, reference being had to the accompanying drawings, in which—

Figure 1 is a perspective view of an ironing-plate embodying my design; and Fig. 2 is an end view, somewhat enlarged, thereof.

As shown in the drawings, the leading feature of my design consists in the conformation given to the ironing-plate, which, as seen most clearly in Fig. 2, is a concavo-convex middle portion A, extending through the greater portion of the width of the plate and

having the two edge portions B B turned upward from the ends of the middle portion A, thus producing curvatures C C of short radius. From the ends of the curved portions C C the edge portions B B extend in straight lines. With reference to a medial plane (indicated by the line x x in Fig. 2) the two sides of the plate are symmetrical. In lines or planes running longitudinally the plate is straight.

What I claim is—

The design for ironing-plates of ironing-machines substantially as shown and described.

ARTHUR R. SELDEN.
